UNITED STATES PATENT OFFICE

2,656,840

TOBACCO SPREADER FOR CIGARETTE
MAKING MACHINESRudolf Fellmann, Prague, Czechoslovakia, as-
signor of one-half to The Skoda Works, Na-
tional Corporation, Plzen, CzechoslovakiaApplication May 2, 1950, Serial No. 159,446
In Czechoslovakia July 9, 1949

5 Claims. (Cl. 131—109)

1

My invention relates to tobacco spreaders for cigarette making machines which include a tobacco feed drum and a tobacco scraper drum within a tobacco hopper or other container. In such machines a tobacco layer or carpet is formed upon the feed drum and the scraper drum rotating in a direction opposite to that of the feed drum is arranged to brush over the surface of the tobacco carpet carried by the feed drum and to brush back any surplus tobacco which may be carried thereby. My invention refers more particularly to means for tamping or compressing the said tobacco layer or carpet to a homogeneous density so that the same will be even and uniform.

It has already been suggested in the art to arrange a plurality of tampers, crushers or other compactors in the bite of said rollers on the tobacco supply side and in addition thereto separate raking means arranged to disperse and to trim tobacco accumulated in said space. As the raking operations and the tamping operations have to be timed the separate tamping and raking devices did not always properly cooperate and they required rather complicated driving means. In addition thereto the raking means which were arranged alternately with the tamping means did not act upon that portion of the tobacco carpet which come under the action of the tamping means.

The object of my invention is to avoid the said disadvantages and other disadvantages which will appear from the following description of an illustrative embodiment of my invention.

The essential feature of my invention consists therein that the tamping and raking operations are performed by the same operational member. For this purpose I use compactors, tampers or the like which are provided with raking projections and which in addition to the up and down movement for the tamping operation perform a timed swing movement away from and back towards the scraper drum. In a preferred embodiment I use tamping bodies or other compacting bodies which are provided with raking projections and are pivotally connected to a reciprocating supporting member, the pivotal connection permitting said tamping bodies to swing away from and back towards the scraper drum in the interval between two succeeding tamping operations so that during the first part of said swing movement the raking projections upon the tamping bodies disperse and trim accumulated surplus tobacco. The pivotal connection between said supports and said tamping bodies will permit the latter to adjust their position during the tamping

10 operation to effectively conform to the surplus tobacco heaped up in front of the bite of the drums.

15 The objects of my invention will be more fully understood from the following specification when taken with the accompanying drawing in which

Fig. 1 shows a side view of my new tamping device,

Fig. 2 a top view thereof.

Fig. 3 a side view of a tamping body in an intermediate position during its swing movement and of the adjoining parts of the driving mechanism, and

Fig. 4 a detail later more particularly referred to.

The same reference characters indicate the same parts in all figures.

20 The tobacco spreader illustrated in Figs. 1 and 2 comprises a carded tobacco feed drum 2 and a carded tobacco scraper drum 1 which are arranged within a hopper or other storage chamber not shown in the drawing. The scraper drum 1 which rotates in a direction opposite to that of the feed drum 2 brushes over the surface of the tobacco layer or carpet carried by the feed drum 2 removing any surplus tobacco which may be carried thereby. The said rollers may be driven in any convenient manner.

25 The tobacco in front of the bite of said rollers 1 and 2 is compressed against the carding of the feed drum 2 by a plurality of tampers or other compactors 8 which are raised and then permitted to fall upon the tobacco layer. Each of these tampers 8 is supported at the end of the longer arm of one of a plurality of swing levers, two such levers 4 and 5 being shown. These levers are rotatably mounted upon the shaft 3 which is parallel to the axes of said drums 1 and 2. Each swing lever is formed by two parallel flat irons or the like. The shorter arms thereof are connected by a cross plate 6 and the longer arms thereof by a pin 7 which pivotally supports one of said tampers or compactors 8.

30 35 40 45 The said swing levers 4, 5 perform a reciprocating movement about the shaft 3 so that the tampers 8 move up and down and perform the required tamping operation upon the tobacco layer carried by the feed drum 2. Neighboring swing levers 4, 5 perform said reciprocating movement alternately that is one lever swings upward while the other lever swings downward and vice versa.

45 50 55 In Fig. 1 the tamper 8 attached to the swing lever 5 is shown in its lifted position and the tamper 8 attached to the swing lever 4 in its position at or near the end of the downward tamping

movement. Fig. 3 shows an intermediate position of a tamper 8 while such tamper is being lifted.

The driving mechanism for said swing levers operates as follows:

A sprocket wheel 24 mounted upon the shaft 26 is driven by a chain 25. A connecting rod 23 is with one end eccentrically connected to said sprocket wheel 24 and with its other end to a crank web 22 which is fixed to said shaft 3 imparting to the same the said rotational swing movement. A toothed segment 19 is also fixed on said shaft 3 and this segment cooperates as shown in Fig. 4 over a pinion 21 with another toothed segment 20 fixed upon another shaft 17 which is parallel to shaft 3. Thus the shaft 17 is forced to swing simultaneously with but in a direction opposite to the shaft 3. Arms 15 and 18 are alternately fixed upon the shafts 3 and 17, respectively, and each of said arms 15 and 18 presses by means of a set screw 16 upon the cross plate 6 of one of said swing levers so that the tamper 8 supported by said swing lever is lifted to its starting position for the tamping operation whereupon said tamper falls downward under its own gravitational force.

According to my invention each tamper or other compactor 8 is pivotally connected to its supporting swing lever 4 and 5, respectively so that the same may swing away from and back towards the scraper drum, and each of said tampers is provided with raking projections 9 and possibly 13 acting upon the tobacco accumulated in front of the bite of the drums 1 and 2. The said swing movement of each tamper 8 is effected in the interval between two succeeding tamping operations by a driving mechanism operating as follows:

Each tamper 8 is provided on its front face with an upwardly extended cover plate 12 the upper part of which cooperates with an arm 27 provided with a pulley 28. The arms 27 are fixed upon said shaft 26 and neighboring arms 27 are angularly shifted by 180°. A spring 10 arranged on the pin 7 forces each tamper 8 towards the scraper drum 1. It will be understood that the rotating arms 27 through their pulleys 28 and said cover plate 12 will swing the respective tamper 8 away from the scraper drum 1 after the tamper reaches its lowest position upon completing of the tamping movement (Figs. 1 and 3) that the raking projections 9 and possibly 13 will be operative during this part of the swing movement. The tampers 8 are released by said arms 27 for a return swing movement towards the scraper drum 1 under the influence of said springs 10 as soon as the tamper 8, for example, the one attached to swing lever 5 as illustrated in Fig. 1, reaches its highest position. The position of each back swung tamper 8 may be controlled by an adjusting screw 11 mounted upon each swing lever 4, 5, and cooperating with a stop face arranged upon each tamper 8.

Although one form of my invention has been shown and described by way of illustration, it will be well understood that my invention may be constructed in various other embodiments which come within the scope of the appended claims.

What I claim as my invention is:

1. In a tobacco spreader for cigarette making machines including a tobacco feed drum and a tobacco scraper drum cooperating therewith, the improvement comprising in combination a plurality of flat-faced tamping bodies to compress the tobacco upon said feed drum, said bodies mounted in front of the bite of said drums, an

up and down swinging support for each tamping body, an articulate connection between each of said supports and each tamping body to support the same swingably thereupon, resilient means holding each tamping body tilted towards the bite of the drums, raking projections upon each tamping body to move surplus tobacco away from the scraper drum, driving means to effect the up and down swinging movement of said supports in alternating order, and driving means to effect a swinging movement of each tamping body away from the scraper drum immediately after it reaches its lowermost position.

2. In a tobacco spreader for cigarette making machines including a tobacco feed drum and a tobacco scraper drum cooperating therewith, the improvement comprising in combination a plurality of flat-faced tamping bodies to compress the tobacco upon said feed drum, said bodies mounted in front of the bite of said drum, a plurality of parallel swing levers oscillating in planes perpendicular to the axes of said drums, an articulate connection between each of said levers and each tamping body to support the same swingably thereupon, resilient means holding each tamping body tilted towards the bite of the drums, raking projections upon each tamping body to move surplus tobacco away from the scraper drum, driving means to effect the up and down swinging movement of said levers in alternating order, and driving means to effect a swinging movement of each tamping body away from the scraper drum immediately after it reaches its lowermost position.

3. In a tobacco spreader according to claim 2, cooperating adjusting means upon each swing lever and each tamping body pivotally connected thereto to control the degree of swing motion of each tamping body relative to the supporting swing lever.

4. In a tobacco spreader according to claim 2, driving means to effect the said swing movement of said swing levers in alternating order comprising a first shaft arranged in parallel to the axes of said drums, said first shaft supporting said swing levers for free pivotal movement thereupon, driving means to impart a rotational swing movement to said first shaft, a second shaft parallel to said first shaft, driving means to impart to said second shaft a rotational swing movement in opposite direction to that of the first shaft, and a plurality of arms fixed alternately to the first shaft and to the second shaft, respectively, each arm adapted to impart to one swing lever the said swing movement in a plane perpendicular to the axis of the scraper drum.

5. In a tobacco spreader for cigarette making machines according to claim 4, adjusting means upon each of said arms to control its cooperation with its respective swing lever.

RUDOLF FELLMANN.
